UNITED STATES PATENT OFFICE.

GEORGE BEUOY, OF CEDAR VALE, KANSAS.

ROTARY ENGINE.

1,127,723.

Specification of Letters Patent.

Patented Feb. 9, 1915.

Application filed November 29, 1913. Serial No. 303,737.

To all whom it may concern:

Be it known that I, GEORGE BEUOY, a citizen of the United States, residing at Cedar Vale, in the county of Chautauqua and State of Kansas, have invented certain new and useful Improvements in Rotary Engines, of which the following is a specification, reference being had to the accompanying drawings.

10 This invention relates to new and useful improvements in rotary gas engines and the primary object of the invention is to provide a device of this character which is capable of being operated by means of an explosive mixture of any desired character whatsoever or by means of fluid pressure.

A further object of the invention resides in providing an engine in which a maximum amount of power may be derived from 20 a minimum amount of fuel consumption.

A further object of the invention resides in providing a device which is simple and durable in construction, inexpensive to manufacture and one which will be very efficient 25 and useful in operation.

With these and other objects in view, the invention consists in the novel features of construction, combination and arrangement of parts as will be hereinafter referred to 30 and more particularly pointed out in the specification and claims.

In the accompanying drawings forming a part of this application, Figure 1 is a vertical section through a device constructed in 35 accordance with my invention, showing parts thereof in elevation. Fig. 2 is a vertical section as seen on line 2—2, of Fig. 1. Fig. 3 is a horizontal section through the device. Fig. 4 is a plan view thereof. Fig. 40 5 is a perspective view of one of the inlet valve members used on the device; Fig. 6 is a detail section showing the pistons or plungers in the feed cylinders, respectively in their operative and inoperative positions. 45 Fig. 7 is a detail side elevation of one of the rocker arms for operating the sparking device; Fig. 8 is a detail view showing the gas supply connections between the carburetor and the cylinders provided with regulating 50 valves.

In describing my invention, I shall refer to the drawings in which similar reference characters designate corresponding parts

throughout the several views and in which 1 indicates a base or foundation, such as is usually provided for devices of this character, upon which is mounted in the usual or any preferred manner the two sections of a casing or housing 2, said casing or housing forming substantially a cylinder for the device. The cylinder 2 formed by the sections of the casing or housing is flat or of reduced thickness for the greater portion of its area, the outer portion thereof being increased, as shown at 3 and designed substantially rectangular in cross section. This outer portion of the cylinder indicated as 3, continues completely around the housing forming an annular enlarged space in which the gases, to be hereinafter referred to, are 70 received.

Mounted in the cylinder or housing 2, is a disk-like rotor 4 which fits snugly between the walls of the flat reduced portion of said cylinder and has formed on the outer peripheral edge thereof at predetermined points thereon one or more head members or the like 5 which fit within the annular space of the latter. As many of these head members may be provided as are found desirable 80 and thus the power of the device may be increased accordingly and each of said head members is provided with a plurality of extension members 5', as clearly disclosed in Fig. 1 of the drawings. These head members or projections 5 on the rotor 4 afford a means whereby said rotor may be revolved in the casing or cylinder 2 as the force of the explosions or fluid pressures is directed against said head members and said head 90 members are beveled at their ends, as shown at 6. The outer faces of said head members contact snugly with the outer peripheral wall of the enlarged portion 3 of said cylinder and carried on the central portion of the 95 disk-like rotor 4 to project through openings in the sides or sections of the cylinder, is a shaft 7. Adjustably mounted on the base or, foundation 1, on opposite sides of the cylinder, are the bearings 8 which rotatably receive therein the projecting portions of the shaft 7. As undue wear occurs between the shaft, foundation and cylinder, the same may be taken up readily by the adjustment of said bearings 8, as is obvious, 105 and a pulley is carried on one end of said

shaft 7, whereby the power derived in the operation of the engine may be transmitted to any desired device (not shown).

- I have provided for the inlet of the explosive mixture or fluid pressure at the top of the cylinder or housing 2, at which point a pair of openings 9, arranged in spaced relation to one another, are provided. These form the actual inlet openings for the cylinder and a pair of the same are provided in order to provide for the reversing of the rotor, which will be hereinafter and more particularly set forth. Mounted on the housing or cylinder 2, over the openings 9, are the cylinders 10 which form feed cylinders, the same being independent of one another and having connection at points below the centers thereof, with a carbureter 11 of any preferred design. As shown in Fig. 8 of the drawings, the connections, between the carbureter and cylinders 10 may be provided with suitable valves whereby the supply of the gaseous mixture to the cylinders may be regulated as desired.
- Arranged in each of the cylinders 10 in planes slightly below the centers thereof, are the dividing walls 12 which provide a pair of compartments in each cylinder and each division wall 12 is provided with a check valve 13, the purpose of which will be hereinafter and more particularly set forth. Hingedly mounted at the lower ends of said cylinders and opening downwardly through the openings 9 in the cylinder or housing 2, are the plate-like valve members 14. These plate-like valve members operate oppositely in order to permit one of the same to be in its inoperative position while the other is operating, and the side edges of said plate-like valves are provided with side flanges 15 projecting on both sides of the plate valve proper. These plate-like valve members 14 are designed to complete the formation of the annular space inclosed by the enlarged portion 3 of the cylinder 2 when said valve members are disposed to their closed positions and the outer side edges of these valve members 14 project slightly beyond the side walls of the enlargements 3 of the cylinders and fit in offsets 15' formed in the latter. This construction admits of the rotor being operated without interference with said valve members and in view of the construction shown and described, no appreciable amount of compression will be lost.
- Loosely extending through the top wall 12 of each of the cylinders 10 is a rod 16, the lower end of which is pivotally connected to a link 17, the latter in turn being pivotally connected to the upper face of a valve member 14. The upper ends of said rods 16 are removably secured to the hollow piston or plunger heads 18 which fit snugly in the cylinders 10 and coil springs 19 are
- arranged in each of the cylinders to contact at their lower ends with the lower walls of the hollow piston heads 18 and rigidly secured at their upper ends to transverse pieces 20 secured to the upper ends of said cylinders. The normal tendency of these springs is to force downwardly upon the piston heads, which operation will obviously cause the valve members 14 to be opened and an adjusting means 21 is provided in connection with the pieces 20 and the upper ends of said springs, whereby the tension of the latter may be adjusted. Inasmuch as but one of the valve members 14 may be operated at a time, a means is provided for retaining one valve member in its closed position at all times. This is accomplished by means of a rocking arm 19' which is mounted at the upper ends of said cylinders, the ends of which are indicated as 19^a, project over the respective cylinders. Hook members 19^b are carried on the pistons 18 which are adapted to be engaged with the ends 19^a, one at a time and as shown in Fig. 6 of the drawings, one piston head 18 is hooked in its inoperative position, while the other is operated.
- It will be understood that as the rotor is revolved in the housing or casing 2, the head pieces or projections 5 thereon are adapted for contact with the depending or open plate-like valve 14, to force the same upwardly to its closed position. As the same is forced to its closed position, the rod 16 will be forced upwardly and the springs 19 compressed. As the rod 16 is forced upwardly, the plunger or piston head 18 thereon will also be raised and in so doing, a charge of gas will be received in the cylinder 10 from the carbureter 11.
- As soon as the projection or head piece 5 passes the opening covered by the valve member 14, said valve is forced by the pressure of the gas within the cylinder 10 and the action of the spring 19 to its open position. As the valve is opened, the piston or plunger head 18 will also be forced downwardly to compress the gases against the division wall 12 and such compression will also open the check valve 13 and permit said gases to be released to the lower compartment of the cylinder 10. In this lower compartment of the cylinder 10, at the lower portion thereof, is mounted a spark plug 22 which is connected to a sparking apparatus (not shown) in the usual or any preferred manner. The device is so timed that the compressed gases which are forced into the lower compartment at this particular time will be fired and the force of the explosion directed against the adjacent face of the head or projection 5 on the rotor 4 which, at this time, is at a point immediately adjacent the valve member 14. The space inclosed between the one face of

the projection or head member 5 on the rotor and the valve member 14, when the latter is in its lowered position may, for convenience, at the time of the explosion, be 5 termed a firing chamber and is indicated as 23. It might here be stated that this 10 sparking device is timed according to the position of the piston or plunger head 18. In order to carry out this purpose, a projection 23' is provided on the transverse 15 piece 20 of each feed cylinder which has fulcrumed thereon, a rocking arm 23a. One end of the rocking arm is connected by means of a link 23b to the piston head in 20 the adjacent cylinder and the other end of the rocking arm is connected by means of a linking arm 23c to any desired operating means (not shown) for coöperation with the sparking device.

25 The force of the explosion will, of course, be directed against the beveled face of the head member or projection 5 on the rotor to cause the latter to be revolved. The gases and other products of combustion will be carried through the space inclosed by the enlarged portion 3 to a point on the device immediately opposite that in which the openings 9 are provided. An exhaust 24 is provided in the base 1 which communicates 30 with the annular space at such point and affords an outlet for the products of combustion and burnt gases. This operation may be continued and when it is desired to reverse the operation of the rotor, the rocking 35 arm 19' is disengaged from the one piston head 18 to which it was engaged previously and rocked to the opposite position, and linked or hooked into engagement with the piston head 10 which was previously in operation. The explosions which will now 40 take place in the device will be directed against the opposite faces of the rotor projections or heads 5 to cause the rotor to be rotated in the opposite direction. The device will be actuated in identically the same 45 manner as before but the direction thereof will be reversed.

The usual oiling devices and a water jacket may be provided for this engine, if 50 desired. If it is found desirable and necessary, a governor may also be used in connection with the device.

While I have shown and described my device particularly adapted for use in connection with a carbureter, wherein explosive gases are supplied to the feed cylinders of the device, it will be understood that the same may be operated through the medium of various other forms of fuel. Fluid pressure is equally well adapted for use in connection with this device and, of course, under these conditions, certain features of the device may be omitted. The device as shown, however, is particularly well adapted for 65 use with a powder mixture and it will be

understood that any form of explosive may be used in connection therewith.

From the foregoing it will be seen that I have provided a device which is simple and durable in construction, inexpensive to 70 manufacture and one which will be very efficient and useful in operation. While I have particularly described the elements best adapted to perform the functions set forth, it is obvious that various changes in form, 75 proportion and in the minor details of construction may be resorted to without departing from the spirit or sacrificing any of the principles of the invention.

Having thus described this invention, 80 what I claim is:—

1. In a rotary engine, a case, a rotor mounted in said case and provided with diametrically opposed arms upon its periphery, said case being further provided with explosion chambers communicating with the interior thereof and a division wall between said chambers, spaced vertical cylinders above the explosion chambers, independently operating pistons in the respective cylinders, valve plates pivotally mounted at one of their ends upon said division wall and operating to close communication between the respective explosion chambers and the interior of the rotor case, links connecting the valve plates to the respective pistons, means for admitting an actuating fluid to the cylinders to be compressed by said pistons, the division wall between each of the explosion chambers and the related piston cylinder being provided with a passage, a valve normally closing said passage, a coil spring acting upon each of the pistons to compress the fluid in the cylinders whereby the valve plate connected to said piston is moved to its open position and said latter valve simultaneously opened to admit the charge to the explosion chamber, and means for holding either of the pistons against movement under action of its spring to retain the valve plate in its closed position. 100

2. In a rotary engine, a case, a rotor mounted therein provided with diametrically opposed arms upon its periphery, said case having explosion chambers and a division wall between the same, a cylinder mounted upon the case above each of said chambers and a passage affording communication between the cylinder and the chamber, a valve normally closing such communication, valve plates pivotally mounted at one of their ends upon the opposite sides of said division wall, each of said valve plates being provided upon its longitudinal edges with flanges, the opposed walls of the explosion chambers being recessed to accommodate said flanges, a piston to operate each of the pistons, means connecting said pistons to the respective valve plates, means for supplying an actuating fluid to the cyl- 125 130

inders, springs acting against the respective pistons to compress the fluid and force the first named valve to its open position, the pivoted valve being simultaneously moved to its open position and engaged at its free end upon the periphery of the rotor, a keeper member fixed to one end of said piston, and a manually operable latch device adapted to be engaged with either of the keepers to

hold the piston against movement under 10 action of the spring to retain the valve plate in its closed position.

In testimony whereof I hereunto affix my signature in the presence of two witnesses.

GEORGE BEUOY.
